MUSIC RACK

Charles Eccher, Brooklyn, N. Y.

Application May 6, 1940, Serial No. 333,683

4 Claims. (Cl. 84—502)

My invention relates to improvements in music racks, the principal object being to equip a music rack inexpensively for quick turning of the pages of sheets, or books, of music, by operation of foot pedals so that a musician reading the music need not take his hands off his instrument at any time.

The accomplishment of the above and subordinate objects presently appearing, a preferred embodiment of my invention is illustrated in the accompanying drawings, set forth in detail in the succeeding description, and defined in the claims appended hereto.

In said drawings:

15. Figure 1 is a view in front elevation of the preferred embodiment of my invention,

Figure 2 is a view in side elevation,

Figure 3 is a fragmentary view in horizontal section taken on the line 3—3 of Figure 1 and 20 drawn to an enlarged scale,

Figure 4 is a fragmentary view in vertical transverse section taken on the line 4—4 of Figure 1,

Figure 5 is a detail view in longitudinal section of part of one of the frames,

Figure 6 is a fragmentary view in perspective of one of the pages of music equipped with armature plates, and

Figure 7 is a fragmentary view in longitudinal section taken on the line 7—7 of Figure 1.

Referring to the drawings by numerals, the music stand of my invention, or rack, comprises a spider-like base 1 of cruciform shape including a pair of forwardly and rearwardly extending foot bars 2, 3, and a pair of similar laterally extending side bars 4, 5, said bars radiating horizontally from a common center and being surmounted by a circular crown block 6 suitably secured to said base 1 centrally thereof. A tubular section 7 arises from the center of the block 6. A rod-like section 8 is slidably mounted in the upper end of the section 7 for vertical adjustment into different set positions as determined by a bolt 9 extending through section 7 and through a longitudinal slot 10 in section 8, said bolt being equipped with a wing nut 11 by means of which the bolt may be tightened to clamp the section 8 in section 7 in selected positions and thereby vary the height of the stand, or rack, as desired.

The upper end of section 8 has suitably attached thereto a music holder 12 in the form of a panel 13, of wood, or other suitable material, of substantially elongated rectangular form extending lengthwise across the section 8 and cen-

tered thereon in the usual oblique position relative to the axis of the section 8 for a purpose which will be understood.

The lower edge of the panel 13 has depending therefrom a central extension 13' carrying an elongated open front housing 14 extending lengthwise parallel to said edge and provided with a hinged closure flap 14'. The upper edge of the panel 13 has an upstanding similar extension 15 supporting a bar 16 extending parallel with said upper edge. The housing 14 and bar 16 are offset forwardly of the panel 13. The function of the housing 14 and bar 16 will presently appear. As will be understood, from an inspection of Figure 1, the length of the panel 13 is such that it extends at both ends slightly beyond the pages of a piece of sheet music 17, or a book of music, of standard size centered on said panel and having the leaves opened up.

For turning the pages of the piece of music 17 the following means are provided.

Upon opposite sides of the vertical center of the panel 13 is a pair of upright, right and left hand shafts 18, 19, each having its upper end rotatably mounted in the bar 16 by means of an antifriction bearing 17' and its lower end extending downwardly through the housing 14 and rotatably mounted in any suitable manner in the bottom of said housing. The rods 18, 19, extend across the panel 13 close thereto and to the vertical center of the same. The right and left-hand shafts 18, 19, carry a pair of right and left hand page turning frames 21, 22, of generally rectangular form and rod-like material, designed to be oscillated laterally over the piece of sheet music 17 when the latter is opened up, said stretches being spaced outwardly of said edges, and top and bottom stretches 25, 26, similarly extending along the top and bottom edges of said pages, respectively. The stretches 25, 26, are telescopic and provided with set screws 27 so that the frames are extensible laterally to properly position the side stretches 25, 26, relative to pages of different sizes.

A pair of upper and lower electro-magnets 28, 29, are sleeved onto the side stretches 24 of each frame 21, 22, between the upper and lower edges of the piece of music 17. Each pair of electro-

magnets 28, 29, is staggered vertically relative to the other pair for a purpose presently seen.

Each page of the piece of music 17 is provided adjacent the side edge thereof with two pairs of 5 small armature plates fixed thereon on the front and rear sides thereof, respectively, the front and rear pairs 30, 31, being staggered relatively in accordance with the staggered relation of the pairs of electro-magnets 28, 29, on the right and 10 left hand frames 21, 22, respectively, so that the front pairs of armatures 30 will be horizontally aligned with the electro-magnets 28, 29, on the right hand frame 21, and the rear pairs of said armatures 31 with the electro-magnets 28, 29 on 15 the left hand frame 22. The purpose of this arrangement will presently appear.

Overlying the front face of the panel 13 is a smaller rectangular guard plate 18 spaced from said panel to overlie the shafts 19, 20, and form a 20 backing for the piece of music 17, said plate having a bottom edge flange forming a ledge 18' for supporting said music and end flanges 19' attached by bolts 20' to said plate. The plate 18 is provided with a pair of vertically extending slots 25 21' therein arranged so that the cover of the piece of music may be clipped to edges of the slots by paper clips 22' to hold the piece of music in proper position.

A pair of right and left hand pedals 31, 32, are 30 suitably connected at lower ends thereof to said pedals to extend upwardly therefrom over idler pulleys 36 mounted by brackets 37 on the rear side of the housing 14, said cables being trained from said pulleys 36 through suitable apertures 38 35 in said housing 14 into the latter and then wound around right and left hand shafts 19, 20, respectively, with their upper ends connected to the ends of the housing 14 adjacent opposite ends of the latter, by coil springs 39 attached to screws 40 40 extended through apertures 40' in the sides of the housing 14 and provided with wing nuts 41' so that by turning said nuts the tension exerted by said springs 39 may be varied.

As best shown in Figure 1, the arrangement of 45 the pedals 31, 32, cables 34, 35, and springs 39 is such that normally the springs pull on the cables and tension the shafts 19, 20, against rotation in directions to swing the frames 21, 22 from the described normal positions, and such pull on said 50 cables holds the pedals 31, 32, in elevated position. However, upon depression of either pedal 31, 32, the corresponding shaft 19, or 20, as the case may be, is rotated in the proper direction to swing the frame 21, 22 thereof from normal position 55 across the piece of music 17 and to the opposite side of the axis of the shaft from that normally occupied by the frame.

Referring now to the operation, the piece of 60 sheet music 17 being centered on the panel 13, with its back edge centered between the shafts 19, 20, if it is desired to turn over a page from right to left, in the usual manner, the right hand 65 pedal 31 is depressed, causing rotation of the right hand shaft 19 in the proper direction to swing right hand frame 21 from normal position, and from right to left, over the left hand page, at the end of which operation the upper and lower electro-magnets 28, 29, on said frame attract the upper and lower armature plates 30 on the front 70 face of said page and freeze to the same. This operation stretches the spring 39 of the right hand cable 34 so that upon release of the depressed pedal 32 said spring contracts and pulls on the right hand cable 34 in a manner to rotate 75 the right hand shaft 19 in the opposite direction

to swing said right hand frame 21 from left to right back to normal position. As said frame 21 swings back to normal position, it turns the page from right to left. Due to the fact that the axis of swinging movement of the right hand frame 21 5 is laterally offset to the right of the axis of turning movement of the page, the electro-magnets 28, 29 pull loose from the plates 30 before the page is fully turned, but such release of the plate 10 flips the leaf into fully turned position.

In turning backwards, from left to right, the left hand pedal 32 is depressed. Under depression and release of said pedal 32 the left hand frame 22 is operated in the same manner as left hand frame 24 but reversely, that is to say, first 15 from left to right and from right to left, the electro-magnets 28, 29, on the left hand frame 22 coacting with the armature plates 31 on the rear side of the right hand page substantially as described with reference to turning from right to 20 left, under operation of the right hand pedal.

The foregoing will, it is believed, suffice to impart a clear understanding of my invention without further explanation.

Manifestly the invention, as described, is susceptible of modification without departing from the inventive concept and right is herein reserved to such modifications as fall within the scope of the subjoined claims.

Having thus described the invention, what I 30 claim is:

1. In a music rack, a base, a standard on said base, a holder for a book of music arising from said standard and supporting said book in upright position with the back edge of said book in the vertical center of the holder, and means for turning the pages of said book from right to left and left to right comprising a pair of right and left hand rock shafts, respectively, rotatably mounted on said holder in upright position, a pair of right and left hand frames extending laterally from said right and left hand shafts, respectively, and normally surrounding the marginal edges of right and left hand pages of said book, to be swung forwardly from normal positions under rocking of said right and left hand shafts in one direction, respectively, coacting devices on said frames and pages, respectively, for causing the right and left hand frames to pick up the left and right hand pages, respectively, under such forward swinging thereof and to turn said pages under reverse swinging to normal position, and means to independently rock said shafts in said direction including a pair of right and left foot pedals on said base, said shafts being mounted in laterally offset position relative to the axis of turning movement of said pages to effect disabling of said devices on the pages and frames under reverse swinging of the latter to normal position whereby said pages are released in the fully turned position thereof by said frames.

2. In a music rack, a base, a standard on said base, a holder for a book of music arising from said standard and supporting said book in upright position with the back edge of said book in the vertical center of the holder, and means for turning the pages of said book from right to left and left to right comprising a pair of right and left hand rock shafts, respectively, rotatably mounted on said holder in upright position, a pair of right and left hand frames extending laterally from said right and left hand shafts, respectively, and normally surrounding the marginal edges of right and left hand pages of said book, to be 60 65 70 75 80 85 90 95 100 105 110 115 120 125 130 135 140 145 150 155 160 165 170 175 180 185 190 195 200 205 210 215 220 225 230 235 240 245 250 255 260 265 270 275 - swung forwardly from normal positions under rocking of said right and left hand shafts in one direction, respectively, coacting devices on said frames and pages, respectively, for causing the 5 right and left hand frames to pick up said left and right hand pages, respectively, under such forward swinging thereof and to turn said pages under reverse swinging thereof to normal position, and means to independently rock said shafts in 10 said direction, said coacting devices comprising a pair of armature plates on the front of each page fixed to and spaced along the front edge thereof, a pair of similar plates on the back of each page 5 fixed to and spaced along said edge thereof, pairs of electro-magnets on said frames, respectively, for freezing to the front and back pairs of armature plates, respectively, under forward swinging of the frames, said shafts being laterally offset 10 from the axis of turning movement of said pages to cause said pairs of electro-magnets under reverse swinging of said frames to pull loose from said armature plates and release said pages in the fully turned positions thereof. 15
- 15 and a pair of electro-magnets on each frame spaced along the same, the armatures on the front of the page being differently spaced relative to those on the back, and the pairs of electro-magnets on the frames being spaced in correspondence to the spacing of the pairs of armature plates on the front and back of the pages, respectively, whereby each pair of electro-magnets is supplemental to one pair of armature plates solely to prevent turning of the pages by 20 the frames under forward movement of the latter. 25
3. In a music rack, a base, a standard on said base, a holder for a book of music arising from said standard and supporting said book in upright position with the back edge of said book 30 in the vertical center of the holder, and means for turning the pages of said book from right to left and left to right comprising a pair of right and left hand rock shafts, respectively, rotatably mounted on said holder in upright position, a pair 35 of right and left hand frames extending laterally from said right and left hand shafts, respectively, and normally surrounding the marginal edges of right and left hand pages of said book, to be swung forwardly from normal positions under rocking of said right and left hand shafts in one direction, respectively, coacting devices on said frames and pages, respectively, for causing the right and left hand frames 40 to pick up said left and right hand pages, respectively, under such forward swinging thereof and to release said pages under reverse swinging thereof to normal position, and means to independently rock said shafts in said direction including a pair of right and left foot pedals on said base, a pair of pull cables connecting said 45 right and left foot pedals to said right and left hand shafts, respectively, and wound around the latter, and spring means coacting with said cables to tension said shafts and frames against operation from normal position.

CHARLES ECCHER.
